UNITED STATES PATENT OFFICE.

GEORGE H. RICHARDS, OF MEMPHIS, TENNESSEE.

DESIGN FOR A SHOE-LACE FASTENER.

SPECIFICATION forming part of Design No. 31,241, dated July 18, 1899.

Application filed June 20, 1899. Serial No. 721,247. Term of patent 3½ years.

To all whom it may concern:

Be it known that I, GEORGE H. RICHARDS, of Memphis, in the county of Shelby and State of Tennessee, have invented and produced a new and original Design for a Shoe-Lace Fastener, of which the following is a full, clear, and exact specification.

Reference is to be had to the accompanying drawings, forming a part of this specification, in which similar characters of reference indicate corresponding parts in all the views.

Figure 1 is a perspective view of the shoe-lace fastener, showing my design. Fig. 2 is a front elevation of the same, and Fig. 3 is a sectional side elevation of the same.

The design in its entirety consists of a cylindrical hollow base A, formed with a flanged upper end A', from which rises a curved

shank B, terminating in one side of an approximately spherical head C, extending with its bottom within a short distance of the flat top of the base and forming with the said base-top and the shank a lace-receiving recess D, increasing in size in a rearward and upward direction, as is plainly indicated in Fig. 3.

The leading features of the design consist of the base, the shank, and the spherical head.

I claim—

The design for a shoe-lace fastener herein shown and described.

GEORGE H. RICHARDS.
